[57] CLAIM

The ornamental design for headwear incorporating audio earphones, as shown and described.

DESCRIPTION

FIG. 1 is an isometric view of headwear incorporating audio earphones showing my new design, the cord is drawn broken away to show indeterminate length;
FIG. 2 is a top plan view thereof;
FIG. 3 is a front elevational view thereof;
FIG. 4 is a rear elevational view thereof;
FIG. 5 is a side elevational view thereof, the opposite side is a mirror image;
FIG. 6 is an isometric view of a second embodiment of headwear incorporating audio earphones showing my new design;
FIG. 7 is a top plan view thereof;
FIG. 8 is a side elevational view thereof, the opposite side is a mirror image;
FIG. 9 is a bottom plan view thereof;
FIG. 10 is a front elevational view thereof; and,
FIG. 11 is a rear elevational view thereof.
